INVENTOR

Nathan Kaplan
BY
Edward D. Marr
ATTORNEY

UNITED STATES PATENT OFFICE.

NATHAN KAPLAN, OF NEW YORK, N. Y.

GARMENT-SUPPORTER.

1,284,704.

Specification of Letters Patent. Patented Nov. 12, 1918.

Application filed September 21, 1917. Serial No. 192,435.

To all whom it may concern:

Be it known that I, NATHAN KAPLAN, a citizen of the United States, and resident of the borough of Manhattan, county of New York, city and State of New York, have invented certain new and useful Improvements in Garment-Supporters, of which the following is a specification.

The device the subject of this invention is a combination of a waist line body belt, performing all of the functions of an ordinary belt but having secured thereto a suspender passing over the shoulders and engaging with the belt at a plurality of points.

The object of the invention is to provide a firm yet flexible supporter for the trousers and one which may be adapted for all general uses.

Should it be desired to use the belt alone the suspenders may be detached, and the securing means removed from the belt with the result that the belt will have the appearance of an ordinary belt.

The following is what I consider a good means of carrying out this invention, and the accompanying drawings form a part of this specification.

Figure 1 is a front perspective view of my complete device.

Fig. 2 shows a securing means.

Fig. 3 shows one of the buttons used in the device shown in Fig. 1, and

Fig. 4 shows a hook which may be used as a substitute for the button.

Similar reference numerals indicate like parts in all the figures where they appear.

At 1, I show a belt which may be formed of leather, webbing or other material, and at one end of the belt 1, I arrange a buckle 2, of ordinary construction and operation.

In the belt 1, I produce a plurality of perforations 3 any one of which may serve with the tongue 4 of the buckle 2 in the adjustment of the belt.

At 5, and 6 I show the shoulder members or straps or suspenders. The members 5 and 6 are brought together in the back and are joined by a metal plate or leather device 7, to which the members 5 and 6 are firmly secured.

Through the member 7 I pass a securing loop 8 each end of which is provided with a button receiving aperture as shown at 9 and 10.

The front side of each of the suspenders 5 and 6 carries an adjusting buckle 11-12, the use of which is well understood. Leather loops 13 and 14 are suspended from metallic loops 15 and 16 movably engaged upon the suspenders 5 and 6, and these leather loops 13 and 14 pass through metal loops 17 and 18 to each of which is secured a single strap or thong 19 or 20. The straps 19 and 20 provide means for securing the front ends of the suspenders to the belt.

Passing through suitably arranged perforations in the belt are buttons such as shown in Fig. 3. The button consists of a button head 21 having an internally screw-threaded shank 22. A screw 23 is adapted to enter the shank 22 and is provided with a button head 24 which may be made of precious metal, or which may be decorated to satisfy individual tastes.

Four of these buttons are engaged in suitable position upon the belt by passing the screw 23 through one of the perforations and firmly screwing the shank 22 upon the screw 23.

The buttons may be all removed when the suspenders are not desired. The belt will then have the appearance of any ordinary belt but with an extended series of adjusting perforations.

In lieu of the buttons shown in Fig. 3 I may employ hooks as shown in Fig. 4 or I may arrange permanently secured buttons upon the interior surface of the belt.

The metal loops shown in Fig. 2, and at 25 in that figure may be secured to the thongs 19-20 and to the ends of the back loop.

Any type of belt may be employed with my device and other modification made within the scope of the appended claims 95 without departing from the principle or sacrificing the advantages of this invention.

Having carefully and fully described my invention what I claim and desire to secure by Letters Patent is:

1. A belt having a plurality of perforations, a plurality of separable buttons adapted to be secured in any of said perforations to be adjustable longitudinally of said belt and shoulder straps engaged upon said buttons.

2. A device of the character described consisting of suspenders, having a back loop

provided with a plurality of downwardly extending ends, each of said ends having a button receiving means, a single thong supported by each shoulder strap of said suspender, and each said thong being provided with a single button engaging perforation and a belt having a plurality of perforations and buttons adjustable longitudinally

of said belt by virtue of being adapted to be engaged in any of said belt perforations. 10

Signed at New York city, in the county and State of New York this 6th day of Sept., 1917.

NATHAN KAPLAN.

Witness:

G. E. S. MARR.
